UNITED STATES PATENT OFFICE.

EDGAR M. BOTTOME, OF MOUNDSVILLE, WEST VIRGINIA, ASSIGNOR TO FOSTORIA
GLASS COMPANY, OF MOUNDSVILLE, WEST VIRGINIA, A CORPORATION OF WEST
VIRGINIA.

DESIGN FOR A GOBLET.

Application filed July 2, 1928. Serial No. 27,350. Term of patent 14 years.

To all whom it may concern:

Be it known that I, EDGAR M. BOTTOME, a citizen of the United States, residing at Moundsville, in the county of Marshall and State of West Virginia, have invented a new, original, and ornamental Design for Goblet, of which the following is a specification, reference being had to the accompanying drawing, forming part thereof.

The figure is a perspective view of the goblet, showing my new design.

I claim:

The ornamental design for a goblet, as shown.

EDGAR M. BOTTOME.
